Primary Examiner — Jennifer Rivard

Assistant Examiner — Jonathan E Fiencke

(57) **CLAIM**

The ornamental design for a cover for a bathtub overflow system, as shown and described.

DESCRIPTION

FIG. 1 is a front-top perspective view of an exemplary cover for a bathtub overflow system.

FIG. 2 is a rear-bottom perspective view of the cover for a bathtub overflow system of FIG. 1.

FIG. 3 is a front view of the cover for a bathtub overflow system of FIG. 1.

FIG. 4 is a rear view of the cover for a bathtub overflow system of FIG. 1.

FIG. 5 is a right side view of the cover for a bathtub overflow system of FIG. 1.

FIG. 6 is a left side view of the cover for a bathtub overflow system of FIG. 1.

FIG. 7 is a top view of the cover for a bathtub overflow system of FIG. 1; and,

FIG. 8 is a bottom view of the cover for a bathtub overflow system of FIG. 1.

The broken lines depict portions of the cover for a bathtub overflow system that form no part of the claimed design.

1 Claim, 8 Drawing Sheets
